UNITED STATES PATENT OFFICE.

JOSEPH MOLTAR, OF FORT RILEY, KANSAS.

HOLDER.

1,103,367.

Specification of Letters Patent.

Patented July 14, 1914.

Application filed August 18, 1913. Serial No. 735,394.

To all whom it may concern:

Be it known that I, JOSEPH MOLTAR, a citizen of the United States, serving in the United States Army, Troop I, Thirteenth Cavalry, at present stationed at Fort Riley, in the county of Geary and State of Kansas, have invented a new and useful Improvement in Holders, of which the following is a specification.

10 This invention relates to a readily attachable and removable holder adapted to hold table cloths, oil cloths or other coverings upon tables or benches, or covers upon mantel pieces, or paper upon a drawing board, 15 or upon an easel, or the device may be employed in many other ways for holding various articles in place. The device is also adapted for use as will hereafter appear as part of a temporary coat or hat rack being 20 readily attachable to the side of a shelf, mantel piece or the like.

The invention consists in the novel features of construction hereinafter described, 25 pointed out in the claims and shown in the accompanying drawings, in which:

Figure 1 is a perspective view illustrating the device in position, a portion of a bench or table being indicated in dotted lines. Fig. 2 is a section on the line 2—2 of Fig. 1. 30 a locking bar being shown in dotted lines in one of its several positions. Fig. 3 is a detail longitudinal section through the outer end portion of the device. Figs. 4, 5 and 6 are plan views of the blanks from which the 35 body portions of the device are formed. Figs. 7 and 8 are detail plan views of certain locking devices.

With the exception of the wedge shaped locking devices shown in Figs. 7 and 8 the 40 device consists of three separate parts adapted to be fitted together and the construction of these parts will be best understood by first describing the blanks shown in Figs. 4, 5 and 6. The top member is formed from a blank A slightly enlarged and rounded at one end and having lateral extensions A' at the opposite end, and said end portion is adapted to be bent at a right angle to the body portion of the blank while extensions 45 A' are also bent along the dotted lines for the purpose of forming guide ways. The bottom member is formed from a blank B having parallel tongues 5 at one end, one of 50 which has its inner face toothed as indicated in the drawings, and the marginal side

portions B², of the blank B are bent over and then back upon the body portion thereof forming substantially a flat open sleeve, and the sides of said sleeve are provided with longitudinal slots as indicated in the blank 60 at B³. The locking bar shown in Fig. 6 consists of a flat metal blank C suitably perforated near one end and a nut C' may be soldered or otherwise secured upon one face of the blank and in alinement with the perforation, or the nut may be formed upon the blank in the form of a boss with a threaded perforation therethrough.

The complete article itself after being suitably formed from the blanks above described consists of a top member 1 adapted to lie flat upon the top of the table cloth, a sheet of drawing paper, or other material to be fastened in position and said member has its outer end bent to form a depending 70 flange 2, which is of greater width than the top member and the sides of said flange are bent over back upon the inner side as indicated at 3 to form guide ways, the member 1 being transversely slotted as shown at 3^a, 80

said slot opening between the guide ways formed by the bent portions 3. A bottom member consists of an open flat sleeve 4 having at its outer end upturned tongues 5 which are adapted to enter the guide way 85 formed by the members 3 of the flange 2. The sides of the flat sleeve 4 are slotted as indicated at 6 and a flat locking bar 7 is adapted to slide into the inner end of the sleeve 4 as shown in Fig. 1, or it may be 90 passed through slot 6 so as to rest transversely across the sleeve as shown by dotted lines in Fig. 2. A suitable locking bolt in the form of a wing bolt 8 works through a

nut 9 carried by the locking member 7 and 95 bears upon the under surface of the table. In order to lock the top member 1 and the bottom sleeve member 4 together I employ the locking members 10 and 11 as shown in Figs. 7 and 8, respectively, and the member 100 11 is inserted in the slot 4 and is provided with teeth upon one side which mesh with the teeth upon one of the tongues 5. The other locking member 10 is then inserted in the slot and fills the remainder of the space 105 between the two tongues 5 and by forming these devices slightly wedge shaped the teeth of the member 11 will be forced tightly into engagement with the teeth of the tongue 5, thereby preventing the top mem- 110

ber 1 from becoming disengaged from the sleeve 4 until the locking member 10 is removed, after which the member 11 can be readily removed and the parts detached. I 5 also prefer to place upon the inner end portion of the top member 1 a ring or socket 12 which may be employed for the purpose of holding a candle or it may form a socket into which a suitable candle holder may be 10 threaded, or if the device is designed to be used as a hat or coat hanger the parts may be suitably clamped in position and pin, plug or screw, not shown may be threaded into the socket 12 thereby forming a holder 15 for the hat or coat. The device is capable of a variety of uses and is adapted to fit either square or round tables, and can be placed either at the corners or midway the ends of a table.

20 What I claim is:—

1. A holder for flexible sheets comprising upper and lower members adapted to lie parallel to each other when in normal position, means for connecting said members, 25 one of said members having a longitudinally extending guide-way, said guide-way being provided with longitudinal slots, and a slide-able locking member adapted to slide longitudinally in said guide-way or to pass trans-

versely across said guide-way through said 30 slots.

2. A holder of the kind described comprising a top member having an angled guide-way at one end, and slotted in alinement with said guide-way, a lower member having tongues at right angles to said member, 35 said tongues being adapted to enter said guide-way and means adapted to enter the slot and engage said tongues for the purpose of locking said lower member and said top 40 member together.

3. A holder of the kind described comprising a top member having an angled guide-way at one end and slotted adjacent said guide-way, a lower member having tongues 45 at right-angles thereto, said tongues entering said guide-way, one of the tongues being toothed upon its inner side, a toothed locking member adapted to enter the slot and engage the toothed tongue and the second locking member adapted to fit between the toothed locking member and the remaining tongue.

JOSEPH MOLTAR.
